MEANS FOR GATHERING OR PLAITING TEXTILE AND LIKE MATERIAL PREPARATORY TO SMOCKING THE SAME

Gabriel Christiaan Erasmus Keet, Johannesburg,
Transvaal, Union of South AfricaApplication November 1, 1939, Serial No. 302,314
In the Union of South Africa November 24, 1938

15 Claims. (Cl. 223—32)

The present invention consists of improvements in means for gathering or plaiting cloth or textile or like materials preparatory to smocking the same.

5 It relates more particularly to a means or machine for the purpose specified wherein a pair of rotated meshing toothed wheels is employed between which the material is passed, and which impart thereto the requisite folding for the gathering or plaiting, the said wheels being grooved or recessed peripherally to provide openings between them, and wherein a plurality of threaded needles are provided the ends of which are arranged in the openings and which are adapted to pass through the folded material to retain the folded formation.

In the operation of the aforesaid means or machine the amount of material which can be gathered or plaited at one time is limited to the amount which can be collected on or taken by the needles, and the object of the present invention is so to construct the means or machine that any length of material can be gathered or plaited thereby.

20 According to the invention the needle holder or carrier is movable or slidable in directions towards and away from the toothed wheels, so that the pointed ends of the needles carried thereby can be moved through the openings provided by and between the wheels. Means are provided for gripping, clamping or holding the needles beyond the wheels or at the opposite side of said wheels to the needle holder or carrier so that the latter can be moved in a direction away from the wheels and the gathered or plaited portion of the material removed from or slid off the threaded needles. The holder or carrier can then again be advanced or moved towards the wheels to engage and grip the needles, and then retracted after release of the needles by the gripping or holding means beyond the wheels to return the points of the needles to their operative positions in the openings to enable more of the material to be gathered or plaited and moved on to the threaded needles.

25 The needle holder or carrier may be in the form of a suitably guided plate or table equipped with spring-operated pivoted resilient means for gripping the needles or holding them in position between it and the plate or table.

The means beyond the toothed wheels or at the opposite side thereof to the needle carrier for gripping or clamping the needles may be in the form of pivoted or lever-operated resilient means adapted to hold the needles against a suitable

surface. Spring means may be provided for retaining said gripping means in its operative position.

Guiding and positioning means is preferably provided for ensuring that the rear ends of the 5 needles will assume their proper positions on the needle holder or carrier when the latter is advanced to engage them.

Means, say in the form of a resilient pad attached to the lever of the needle gripping means 10 beyond the wheels and adapted to be brought into contact with one of the wheels, may also be provided for preventing rotation of the wheels when the needles are being moved or the gathered material removed.

15 The invention also includes other features of construction, hereinafter described and claimed.

The invention will be more fully explained with the aid of the accompanying drawings, wherein—

Fig. 1 is a side elevation of the means or machine. 20

Fig. 2 is a plan of Fig. 1.

Fig. 3 is a central sectional side elevation of portion of the machine illustrated in Figs. 1 and 2.

Fig. 4 is a view similar to Fig. 3 showing certain 25 of the parts in different positions, and

Fig. 5 is a front elevation of portion of the device for guiding the ends of the needles into their correct positions in the needle holder.

Referring now to the drawings in which a practical embodiment of the features constituting the invention is illustrated, 1 denotes the frame, shown of box shape, by which the various parts of the machine are carried. 2 is the one and upper toothed wheel, and 3 the other and lower toothed wheel adapted to mesh with the wheel 2 to impart the folding or plaiting for the gathering of the material which passes between the wheels 2, 3. The teeth of the wheels 2, 3, when meshing allow sufficient clearance between them to permit 40 of the textile material passing between them without cutting or damaging the same.

The lower wheel 3 is provided with end trunnions 4 by which it is rotatably mounted in open-ended bearings 5 formed in the side members 6 45 of the frame 1.

The frame 1 is constructed with openings 7, 8, at the front and rear ends respectively, and openings 9 at the sides to allow of easy access to the material being operated upon. It is shown provided at the bottom with resilient pads 10 by 50 which it is carried.

The upper toothed wheel 2 is rotatably supported through the medium of its end trunnions 11, 12, in a U-shaped member, bale or bridle 13, 55

which is pivotally attached at its rear ends to the upper portion of the sides 6 of the frame 1, by bolts 14. The wheel 2 is provided with a handle 15 for rotating it, which is fixed by a screw 16 to 5 the trunnion 12.

17 are the circumferential or peripheral grooves or recesses shown provided at regular intervals in the upper wheel 2, and extending inwardly to the roots of the teeth, and 18—see 10 Figs. 3 and 4—are the correspondingly positioned shallow circumferential or peripheral grooves or recesses formed in the lower wheel 3. The grooves 17 and 18 in the wheels 2 and 3 respectively form the openings or spaces in 15 which the sharpened end portions of the needles 19 are operatively arranged. The shallow grooves 18 in the wheel 3 are preferably rounded at the bottom and are only deep enough to accommodate the needles 19 and allow them to 20 pass through the spaces or openings, so that the teeth of said wheel 3 act to support the needle ends which are kept pressed against them, as hereinafter described.

The needle holder or means for carrying or 25 supporting the needles 19 includes a plate or table 20, adapted to slide between upper and lower guide strips 21, 22, respectively, at both sides of the frame 1, and fixed, as by welding, to the inside thereof. The plate or table 20 upon 30 its upper surface has fixed to it a further plate 23, which is shown bent over at the forward end, at 23a, to form a stop for the needles 19. The plate 23 is adjustably fixed to the table 20 by bolts 24 which pass through holes in the plate 35 23 and elongated slots 24a in the table 20. This allows the position of the plate 23 to be varied relative to the table 20 to accommodate sets of 40 needles of different length and ensure that when the perforated ends of the needles are against the stop 23a and the table 20 in its rearmost position, the points of the needles 19 will lie approximately centrally between the axes of the 45 wheels 2, 3.

The table 20 is adapted to move within limits 45 and for this purpose stops are provided therefor at both back and front. The stop at the front is provided by a U-shaped piece or bracket 25, the lower central portion 26 of which is fixed, as by welding, to the underside of the table 20 50 near the front, and the upstanding sides 27 of which carry the pivot screws 28 of the needle-gripping device, about to be described, and the spindle 29a of a reel 29 for holding the thread—not shown—for each needle 19. The U-shaped bracket 25 acts as a stop for the table 20 in a 55 rearward direction by engaging with the frame 1 at the back of a recess 30 which it enters. The stop for the table 20 in a forward direction is provided by a transverse piece or strip 31 which, 60 when the table 20 is in its foremost position, engages with the two lower guiding strips 22. The table 20 is constructed with a downturned rear portion 32 for use in moving it backwards and forwards. It is also constructed with an acute- 65 angled downturned forward portion 33 to which is fixed by screws 34 a plate or comb 35 for guiding and centering the needles 19. The plate or comb 35—see also Fig. 5—is formed with inverted V-shaped teeth 36, leaving V-shaped 70 recesses 37 between them in which the needles 19 are arranged.

The needle-gripping device on the table 20 consists of spring-operated means for resiliently 75 pressing the needles 19 down on the table 20 at their rear ends and causing the forward ends to

be pressed down upon the lower wheel 3. For this latter purpose the forward portion of the surface of the table 20 is slightly inclined, as indicated at 20a. The gripping means includes an inclined plate 38, the forward portion of 5 which is bent downwardly at 39, and the rear substantially horizontal portion tapered towards the rear edge 40, which latter is turned inwardly. The plate 38 is constructed with side portions 41 through the medium of which it is pivotally 10 connected to the vertical sides 27 of the U-shaped bracket 25 by the pivot bolts 28. To the downwardly bent portion 39 is fixed by a plate 42 and bolts 43 the gripping pad 44 of rubber or other resilient material. The pad 44 is kept 15 pressed down on the needles 19 to retain them in position by a spring 46 arranged between the underside of the rear portion of the plate 38 and the top of the table 20, and fixed to the latter by a screw 45.

The means for gripping the needles 19 at the front of the wheels 2, 3, in order to allow of the gathered material being removed from the rear ends thereof includes a bracket or U-shaped member 47 arranged transversely of the forward end of the bale or bridle 13, the vertical sides 48 whereof are fixed, as by welding, to the outside of the bale or bridle 13. The central lower portion 49 of the U-shaped member 47 is of inverted channel shape in cross-section and 30 provides on the top a surface 50 upon which the needles 19 are held by the resilient gripping pad or member 51. The pad or member 51 is held between a pivoted bar or plate 52 and a lever plate 53, by bolts 54. The bar or plate 52 is 35 fashioned with side wings or lugs 55 by which it is pivotally connected to the sides of the bale or bridle 13 and sides of the member 47 by pivot bolts 56. The lever plate 53 is shown upwardly directed in its lower portion 57 and tapered and 40 inclined in its upper portion 58. It is turned inwardly at its outer end, as indicated at 59.

Means are provided for retaining the lever plate 53 in the position in which the gripping pad 51 is engaging the needles 19 or the surface 45 50, and such means are shown in the form of a flat spring 60 fixed by a bolt 61 at its lower end to the back of the bale or bridle 13, and formed with a U-shaped bend at 62 to engage the outer inturned end 59 of the lever plate 53. 50

To the lever plate 53, above the pivot bolts 56, is attached by bolt 63 a resilient piece or pad 64 which is adapted, when the needles 19 are being moved in either direction to be brought into contact with the upper wheel 2 to hold the same 55 against rotation and prevent movement of any material that might be in position between the wheels 2 and 3.

70 are holes in the plate 38 to allow of the 60 insertion of a screw-driver to tighten or loosen the screw-bolts 24.

The bale or bridle 13 at its rear end at one side is constructed with an extension 13a which, when the bridle is moved about its pivots 14 to its extreme outward position—in which part of it is shown in dotted lines in Fig. 1—comes into contact with a stop screw 65 fixed in one side 6 of the frame 1. A pin 66 on the extension 13a has attached to it one end of a tension spring 67, the other end of which is attached to a pin 68 on the side of the frame 1. This spring 67 serves to buffer or cushion the downward movement of the bale or bridle 13 and prevent violent contact of the wheel 2 with the wheel 3 or the material 70 75

thereon should the bale or bridle 13 fall or be brought down too violently.

The long reel 29 for carrying the threads for each needle 19 is constructed with a plurality of annular grooves 69, one corresponding in position to each needle 19. The threads may be fixed in cuts or notches at the sides of the grooves 69 in the manner usual with cotton or like reels.

In the operation of the machine I prefer to raise the upper wheel 2 in the bale or bridle 13 and lay the material on the lower wheel 3 in front of the needles 19. The bridle 13 is then lowered to cause the wheel 2 to mesh with the wheel 3 and hold the material between them. The needles 19 are now in the operative position shown in Figs. 1 to 3. Upon rotation of the handle 15 the material is caused to pass through between the wheels 2, 3, and is folded thereby and pierced by and fed or pressed on to the needles 19. When all the material to be gathered, or sufficient of it more or less loosely to fill the needles 19, has been folded and pressed on to the latter, if necessary the flat spring 60 is pressed backwards and the lever plate 53 lowered to bring the resilient pad 64 into contact with the wheel 2 and prevent it rotating. The table 20 is then slid forwards into the position in which it is shown in Fig. 4, which causes the needles 19 to move between the wheels 2, 3, until the ends thereof lie on the surface 50. The lever plate 53 is then moved backwards and causes the gripping pad 51 to grip the needles 19 tightly on the surface 50. The gripping pad 44 carried by plate 38 is now raised to release the perforated ends of the needles 19. The table 20 is then retracted. The material on the needles 19, or most of it, can now be drawn off the rear ends of the needles 19, which have previously been threaded, so that the running threads serve to retain the folded or plaited formation. The table 20 is then again pushed forwards and the rear perforated ends of the needles 19 enter the V-shaped recesses 37 in the comb or plate 35, are centered therein and come into contact with the end 23a of the plate 23; the plate 38 being meanwhile pressed down against the spring 45 at the back thereof to keep the pad 44 raised above the ends of the needles 19. Upon the plate 38 being released it causes the pad 44 again to grip the needles 19 on the table 20. Thereafter the lever plate 53 is again operated to cause the pad 51 to release the sharpened ends of the needles 19 and the pad 64 to hold the wheel 2. The table 20 with the needles 19 gripped thereon is then retracted and the lever plate 53 actuated to release the pad 64 from the wheel 2. The needles 19 now lie with their points centrally between the axes of the wheels 2, 3, and the gathering can again be proceeded with.

The gripping means including plate 38 and pad 44 bends the needles 19 downwardly as illustrated in Figs. 1 and 3 and presses the pointed ends down on the wheel 3 in the grooves 18 therein, and this ensures that the needles 19 pierce the material near the upper edges of the folds. When smocking is proceeded with after gathering in this manner the threads are easily visible and where they pass through the material serve as a guide in the place of the usual dots or marks used in the smocking operation. If coloured threads be used, or threads of a colour contrasting with that of the material the operation of smocking will be further facilitated.

What I claim as my invention and desire to protect by Letters Patent is:

1. In means for gathering or plaiting textile and like material preparatory to smocking the same, the combination with a pair of rotated meshing toothed wheels constructed with circumferential grooves forming openings between them and a plurality of needles the points of which are operatively arranged in said openings, of a needle carrier movable towards the wheels to pass the needles partially through the openings and retractable to leave the needles projecting through the openings or to return them to their operative positions and means located at the opposite side of the wheels to the needle carrier for holding the needles between the wheels to permit the needle carrier to be retracted and the gathered material to be withdrawn from the needles, as set forth. 5

2. In means for gathering or plaiting textile and like material preparatory to smocking the same, the combination with a pair of rotated meshing toothed wheels constructed with circumferential grooves forming openings between them and a plurality of needles the points of which are operatively arranged in said openings, of a needle carrier movable towards the wheels to pass the needles partially through the openings and retractable to leave the needles projecting through the openings or to return them to their operative positions, and consisting of a sliding guided table and means movably connected thereto for gripping the needles between it and the table, and means for holding the needles beyond the wheels to permit the needle carrier to be retracted and the gathered material to be withdrawn from the needles, as set forth. 10

3. In means for gathering or plaiting textile and like material preparatory to smocking the same, the combination with a pair of rotated meshing toothed wheels constructed with circumferential grooves forming openings between them and a plurality of needles the points of which are operatively arranged in said openings, of a needle carrier movable towards the wheels to pass the needles partially through the openings and retractable to leave the needles projecting through the openings or to return them to their operative positions, and consisting of a sliding guided table, lever means pivotally connected thereto and resilient means carried by the lever and adapted to grip the needles between it and the table, and means for holding the needles beyond the wheels to permit the needle carrier to be retracted and the gathered material to be withdrawn from the needles, as set forth. 15

4. In means for gathering or plaiting textile and like material preparatory to smocking the same, the combination with a pair of rotated meshing toothed wheels constructed with circumferential grooves forming openings between them and a plurality of needles the points of which are operatively arranged in said openings, of a needle carrier movable towards the wheels to pass the needles partially through the openings and retractable to leave the needles projecting through the openings or to return them to their operative positions, and consisting of a sliding guided table, spring-actuated lever means pivotally connected thereto and resilient means carried by the lever and adapted to grip the needles between it and the table, and means for holding the needles beyond the wheels to permit the needle carrier to be retracted and the gathered material to be withdrawn from the needles, as set forth. 20

5. In means for gathering or plaiting textile and like material preparatory to smocking the 25

same, the combination with a pair of rotated meshing toothed wheels constructed with circumferential grooves forming openings between them and a plurality of needles the points of which are 5 operatively arranged in said openings, of a needle carrier movable towards the wheels to pass the needles partially through the openings and retractable to leave the needles projecting through the openings or to return them to their operative 10 positions and means for holding the needles beyond the wheels to permit the needle carrier to be retracted and the gathered material to be withdrawn from the needles, said latter means including a part providing a surface and movable 15 means for clamping the needles between it and said surface, as set forth.

6. In means for gathering or plaiting textile and like material preparatory to smocking the same, the combination with a pair of rotated 20 meshing toothed wheels constructed with circumferential grooves forming openings between them and a plurality of needles the points of which are operatively arranged in said openings, of a needle carrier movable towards the wheels to pass the needles partially through the openings and retractable to leave the needles projecting through the openings or to return them to their operative 25 positions and means for holding the needles beyond the wheels to permit the needle carrier to be retracted and the gathered material to be withdrawn from the needles, said latter means including a part providing a surface, lever means 30 pivotally arranged in operative relation to said surface and resilient means carried by said lever and adapted to clamp the needles between it and the surface, as set forth.

7. In means for gathering or plaiting textile and like material preparatory to smocking the same, the combination with a pair of rotated 40 meshing toothed wheels constructed with circumferential grooves forming openings between them, a hinged bridle in which one of said wheels is rotatably mounted and a plurality of needles the points of which are operatively arranged in said 45 openings, of a needle carrier movable towards the wheels to pass the needles partially through the openings and retractable to leave the needles projecting through the openings or to return them to their operative positions and means for holding the needles beyond the wheels to permit the needle carrier to be retracted and the gathered material to be withdrawn from the needles, the bridle being constructed with a part providing a surface transversely thereof, and the needle-holding means including a lever pivoted to the 50 bridle and resilient means carried by said lever and adapted to clamp the needles between it and the surface, as set forth.

8. In means for gathering or plaiting textile and like material preparatory to smocking the same, the combination with a pair of rotated meshing toothed wheels constructed with circumferential grooves forming openings between them, a hinged bridle in which one of said 60 wheels is rotatably mounted and a plurality of needles the points of which are operatively arranged in said openings, of a needle carrier movable towards the wheels to pass the needles partially through the openings and retractable to leave the needles projecting through the openings or to return them to their operative positions and means for holding the needles beyond the wheels to permit the needle carrier to be 65 retracted and the gathered material to be with- 70 75

drawn from the needles, the bridle being constructed with a part providing a surface transversely thereof, and the needle-holding means including a lever pivoted to the bridle, resilient means carried by said lever and adapted to clamp the needles between it and the surface and spring means for retaining the lever in the clamping position, as set forth. 5

9. In means for gathering or plaiting textile and like material preparatory to smocking the same, the combination with a pair of rotated meshing toothed wheels constructed with circumferential grooves forming openings between them, a hinged bridle in which one of said 10 wheels is rotatably mounted and a plurality of 15 needles the points of which are operatively arranged in said openings, of a needle carrier movable towards the wheels to pass the needles partially through the openings and retractable to leave the needles projecting through the openings or to return them to their operative 20 positions, and consisting of a sliding guided table, spring-actuated lever means pivotally connected to the table and resilient means carried by the lever and adapted to grip the needles between 25 it and the table, and means for holding the needles beyond the wheels to permit the needle carrier to be retracted and the gathered material to be withdrawn from the needles, the bridle being constructed with a part providing a surface transversely thereof, and the needle-holding means including a lever pivoted to the bridle and resilient means carried by said lever and adapted to clamp the needles between it and the surface, as set forth. 30 35

10. In means for gathering or plaiting textile and like material preparatory to smocking the same, the combination with a pair of rotated meshing toothed wheels constructed with circumferential grooves forming openings between them and a plurality of needles the points of which are operatively arranged in said openings, of a needle carrier movable towards the wheels to pass the needles partially through the openings and retractable to leave the needles projecting through the openings or to return them to their operative positions, and consisting of a sliding guided table, stops for limiting the movement of the table in both directions and means movably connected to the table for gripping the 40 needles between it and the table, and means for holding the needles beyond the wheels to permit the needle carrier to be retracted and the gathered material to be withdrawn from the needles, as set forth. 45 50 55

11. In means for gathering or plaiting textile and like material preparatory to smocking the same, the combination with a pair of rotated meshing toothed wheels constructed with circumferential grooves forming openings between them and a plurality of needles the points of which are operatively arranged in said openings, of a needle carrier movable towards the wheels to pass the needles partially through the openings and retractable to leave the needles projecting through the openings or to return them to their operative positions, and consisting of a sliding guided table, means movably connected to the table for gripping the needles between it and the table, and an adjustable stop carried by the table against which the ends of the needles engage, and means for holding the needles beyond the wheels to permit the needle carrier to be retracted and the gathered material to be withdrawn from the needles, as set forth. 60 65 70 75 75

12. In means for gathering or plaiting textile and like material preparatory to smocking the same, the combination with a pair of rotated meshing toothed wheels constructed with circumferential grooves forming openings between them and a plurality of needles the points of which are operatively arranged in said openings, of a needle carrier movable towards the wheels to pass the needles partially through the openings and retractable to leave the needles projecting through the openings or to return them to their operative positions, and consisting of a sliding guided table and means movably connected thereto for gripping the needles between it and the table, means for guiding the needles to the table and centering them thereon and means for holding the needles beyond the wheels to permit the needle carrier to be retracted and the gathered material to be withdrawn from the needles, as set forth.
13. In means for gathering or plaiting textile material and the like preparatory to smocking the same, the combination with a pair of rotated meshing toothed wheels constructed with circumferential grooves forming openings between them and a plurality of needles the points of which are operatively arranged in said openings, of a needle carrier movable towards the wheels to pass the needles partially through the openings and retractable to leave the needles projecting through the openings or to return them to their operative positions, and consisting of a sliding guided table, means movably connected thereto for gripping the needles between it and the table and means, in the form of a comb having V-shaped teeth, carried by the table for guiding the needles to the table and positioning them thereon, and means for holding the needles beyond the wheels to permit the needle carrier to be retracted and the gathered material to be withdrawn from the needles, as set forth.
14. In means for gathering or plaiting textile and like material preparatory to smocking the same, the combination with a pair of rotated meshing toothed wheels constructed with circumferential grooves forming openings between them and a plurality of needles the points of which are operatively arranged in said openings, of a needle carrier movable towards the wheels to pass the needles partially through the openings and retractable to leave the needles projecting through the openings or to return them to their operative positions, means located at the opposite side of the wheels to the needle carrier for holding the needles between the wheels to permit the needle carrier to be retracted and the gathered material to be withdrawn from the needles and means for preventing rotation of the wheels when the needles are moved through the openings between them or the material is being removed, as set forth.
15. In means for gathering or plaiting textile and like material preparatory to smocking the same, the combination with a pair of rotated meshing toothed wheels constructed with circumferential grooves forming openings between them, a hinged bridle in which one of said wheels is rotatably mounted and a plurality of needles the points of which are operatively arranged in said openings, of a needle carrier movable towards the wheels to pass the needles partially through the openings and retractable to leave the needles projecting through the openings or to return them to their operative positions, means including a lever pivoted to the bridle and resilient means carried by said lever for holding the needles beyond the wheels to permit the needle carrier to be retracted and the gathered material to be withdrawn from the needles, and means in the form of a resilient pad carried by the lever for preventing rotation of the wheels when the needles are moved through the openings between them or the material is removed, the bridle being constructed with a part providing a surface transversely thereof with which the resilient needle-holding means co-operates to grip the needles, as set forth.

GABRIEL CHRISTIAAN ERASMUS KEET.
